UNITED STATES PATENT OFFICE

2,215,401

ELECTRODE HOLDER AND GUIDE FOR
ARC LAMPSDavid C. McCroskey, Portland, Oreg., assignor of
one-half to Clarence W. Christenson, Portland,
Oreg.

Application December 11, 1939, Serial No. 308,683

1 Claim. (Cl. 176—119)

This invention relates to arc lamps and more particularly to a support and guide for the electrodes or carbons.

An object of this invention is to provide a supporting and guiding structure for carbon electrodes which may be attached to lamp structures at present in use which will permit the burning of a greater portion of the carbon than is at present possible, thus effecting not only a saving in 5 carbon sticks but also in the time necessary to change carbons.

Another object of this invention is to provide an improved carbon holder which is so constructed that the carbon will be firmly held therein with only a very short length of the carbon projecting into the holder, so that the remaining portion may be used in the normal manner.

A further object of this invention is to provide an improved guide including a supporting 20 arm and a slidably guide member for supporting the carbon and the holder.

A still further object of this invention is to provide an improved carbon holder in the form of an elongated bar or rod provided at one end 25 thereof with a pair of resilient clamping jaws which are arcuate in transverse section, the jaws tightly engaging about an end of the carbon which projects only a very short distance inwardly of the jaws, thus having all but about one-eighth of an inch of the carbon for use in 30 forming the desired electric arc.

To the foregoing objects and to others which may hereinafter appear, the invention consists of the novel construction, combination and arrangement of parts as will be more specifically referred to and illustrated in the accompanying drawing wherein is shown an embodiment of the invention, but it is to be understood, that changes, variations and modifications may be 35 referred to which fall within the scope of the invention as claimed.

In the drawing:

Figure 1 is a detail side elevation of a combined support, guide and holder for a carbon electrode associated with feeding means of an 40 arc lamp,

Figure 2 is a detail top plan of the supporting means,

Figure 3 is a sectional view taken on line 3—3 45 of Figure 1, and

Figure 4 is a fragmentary side elevation partly in longitudinal section of the holder.

Referring to the drawing, the numeral 10 designates generally a pair of clamping jaws which 50 are associated with an electrode feeding means

similar to the jaws and feeding means embodied in Patent No. 2,151,194. An electrode holder generally designated as 11 is engaged between the two jaws 10 and comprises a stem or elongated rod 12 which is preferably round in transverse section and the outer end of the stem 12 is provided with a head 14. The head 14 is constructed in the form of a socket provided with a bore 13 extending inwardly from the outer or forward end thereof and the head 14 is provided 5 at diametrically opposite sides thereof with a pair of longitudinally extending openings 15 which extend inwardly from the outer end and terminate at their inner ends in a transversely disposed cylindrical opening 16. This opening 15 10 is substantially equal to the diameter of the bore 13. The openings 15 form a pair of clamping jaws 17 and 18 between which the inner end of a carbon electrode 19 is adapted to engage. The inner terminal portion of the electrode 19 20 is adapted to engage in the bore 13 and the electrode 19 is tightly held between the jaws 17 and 18 by means of a jaw tensioning member 20. The latter constitutes an abutment engageable by the inner end of the electrode 19 for limiting 25 the extent of the insertion of the electrode 19 into the holder. The jaw tensioning member 20 30 comprises a threaded member 21 which engages loosely through an opening 22 provided in the jaw 17 and the jaw 18 is provided with a threaded opening 23 within which the member 21 threadably engages. The outer end of the threaded member 21 is provided with a head 24 which is 35 adapted to engage against the outer side of the jaw 17 and a handle or knob 25 is formed integral with the head 24 and provides a means whereby the tensioning member 20 may be rotated to tension the two jaws 17 and 18. The openings 22 and 23 are preferably positioned forwardly of the transverse opening 16 so that 40 the two jaws 17 and 18 can be readily moved toward each other in order to clamp the inner end of the electrode 19 therebetween. The jaws 17 and 18 are of transversely arcuate configuration and are formed of resilient material so that 45 when the tensioning member 20 is loosened the jaws 17 and 18 will open slightly in order to permit the removal or replacement of the electrode therebetween.

An electrode supporting bar generally designated as 26 is positioned in substantially parallel relation to the holder 11 and comprises an inner base part 27 provided with an opening 28 at its inner end through which an attaching bolt is 50 adapted to engage for attaching the inner end of 55

the base member 27 to the desired part of the lamp structure. In practice, the electrode feeding jaws 10 form part of an arc lamp structure associated with a motion picture projection machine and the base bar 27 is adapted to be secured to the desired portion of the projection machine.

An elongated guide bar 29 is formed integral with the base bar 27 and the guide bar 29 as shown in Figure 2 is substantially wider than the base bar 27. The guide bar 29 is provided adjacent the inner end thereof with an opening 30 which is parallel with the opening 28 and through which an attaching bolt is adapted to engage for mounting the supporting bar 26 in a substantially horizontal position and in parallel relation to the longitudinal axis of the holder 11. A guide bar 29 is provided with an elongated slot 31 formed in the upper surface thereof and a second slot 32 is formed in the lower surface of the guide bar 29 and communicates with the lower end of the slot 31, thereby forming a substantially T-shaped guide slot extending lengthwise of the guide bar 29.

25 A slide member generally designated as 33 slidably engages in the two slots 31 and 32, and the slide 33 is provided with an upper part 34 slidably engaging in the slot 31 and a lower part 35 slidably engaging in the lower slot 32. An upwardly standing electrode guide 36 extends upwardly from the upper surface of the guide bar 29 and is provided with a V-shaped electrode seat 37 within which the electrode 19 is adapted to loosely engage. A base plate 38 is formed integral with the guide 36 and extends at right angles relative thereto. The base plate 38 is substantially wider than the width of the slot 31 and slidably engages on the upper surface of the guide bar 29. The base plate 38 is secured by means of fastening devices 39 to the inverted T-shaped slide 33.

In the use and operation of the combined guide, support and holder, the head 14 of the holder 11 is adapted to initially receive the inner end of the electrode 19. The electrode may have only a very short portion thereof disposed between the jaws 17 and 18 and the projecting portion of the electrode 19 is adapted to engage in the V-shaped seat 37 of the slideable support or guide 36. The inner end of the stem 12 is clamped be-

tween the clamping jaws 10 forming part of the electrode feeding means. As the holder 11 with the electrode 19 is moved relative to an adjacent or confronting electrode 19a, the electrode 19 may slide relative to the guide 36 and this guide 36 may also slide lengthwise of the supporting bar 29. In this manner the electrode 19 will be maintained at all times in axial alignment with the electrode 19a.

A combined support and holder for an electrode constructed according to an embodiment of this invention will permit the use of a greater portion of the length of the carbon electrode than is at present possible, as the electrode 19 may have only a very small portion of the length thereof engaged between the clamping jaws 17 and 18. In practice, there need be only about one-eighth of an inch of the electrode 19 positioned between the jaws 17 and 18. By using the greater portion of the length of the electrode 19, there will be a considerable saving in time required to change the electrodes in addition to a material saving of the electrode itself.

With holders and feeding devices at present available, there is approximately two and one-half inches of electrode which cannot be used due to the fact that the holder and guide means for the electrode will not permit the burning of the electrode for a shorter length.

The hereinbefore described guide and holder 30 may be made in the form of an attachment for the present parts of an arc lamp structure, particularly an arc lamp structure associated with a motion picture projection machine.

What I claim is:

In a combined holder and guide structure for the carbon electrode of an arc lamp, the combination of an elongated supporting bar having its outer portion formed lengthwise thereof with an elongated slot of inverted T-shaped cross section, an inverted T-shaped slide member positioned in said slot, a vertical guide having a V-shaped cut-out adapted for receiving the electrode holder, a flat base plate mounted on the slotted outer portion of said bar and merging at its forward end into the lower end of said guide, and means for connecting the base plate to said slide member whereby the guide will be connected to said bar.

DAVID C. McCROSKEY.
